PORTABLE VACUUM CLEANER CASING

Philip S. Egan, Glenview, Ill., assignor to Sears, Roebuck and Co., Chicago, Ill., a corporation of New York

Application August 26, 1957, Serial No. 47,501

Term of patent 14 years

(Cl. D9—2)

FIG. 1

FIG. 2

Fig. 1 is a front perspective view of a portable vacuum cleaner casing embodying my new design, and

Fig. 2 is a rear elevational view of the same.

The side not shown in the drawing is substantially the same in appearance as the side shown and the bottom is plain.

I claim:

The ornamental design for a portable vacuum cleaner casing, as shown and described.
